UNITED STATES PATENT OFFICE.

MIKE SEPELYAK, OF VERONA, PENNSYLVANIA.

DRAFT APPLIANCE FOR AUTOMOBILES.

Application filed April 12, 1922. Serial No. 551,943.

To all whom it may concern:

Be it known that I, MIKE SEPELYAK, a citizen of Czechoslovakia, residing at Verona, in the county of Allegheny and State 5 of Pennsylvania, have invented certain new and useful Improvements in Draft Appliances for Automobiles, of which the following is a specification.

This invention relates to certain new and 10 useful improvements in draft attachments for automobiles, and has particular reference to an emergency draft appliance to be secured to the automobile for pulling the automobile out of mud holes and the like.

15 The primary object of the invention resides in the provision of a drum adapted to be secured to a driving wheel of the automobile with a cable and pulley arrangement anchored to the ground and secured to the 20 front end of the automobile, and also secured to said drum to be wound on the drum when the driving wheel is rotated to pull the automobile out of a mudhole or the like.

25 A further object of the invention has particular reference to a novel type of drum and a specific connection between the pulling cable and the drum.

With the above objects in view and others 30 that will appear as the nature of the invention is better understood, the same consists in the novel construction, combination and arrangement of the parts hereinafter more fully described, illustrated in the accompanying drawings, and pointed out in 35 the appended claims.

In the drawings forming a part of this application and in which like designating characters refer to corresponding parts throughout the several views:

40 Fig. 1 shows by dotted lines a side elevational view of an automobile with the draft attachment operatively associated therewith.

Fig. 2 is a side elevational view of the drum detached from the driving wheel and 45 showing the pulling cable secured to the drum,

Fig. 3 is an edge elevational view of the drum,

50 Fig. 4 is an enlarged fragmentary side elevational view of the drum showing the tensioned bolt closed recess in a side flange of the drum for retaining one end of the pulling cable,

55 Fig. 5 is a fragmentary top plan view of the drum showing the tensioned bolt closing the open side of the drum flange recess;

Fig. 6 is a detail sectional view taken on line VI—VI of Fig. 4 showing the flange recess and tensioned bolt, and

Fig. 7 is a detail sectional view taken on 60 line VII—VII of Fig. 4 showing the tensioned spring of the recess closure bolt.

Referring more in detail to the accompanying drawings, and particularly to Fig. 1, there is illustrated by dotted lines an automobile embodying a chassis A, and a rear driving wheel B, the emergency draft appliance associated with the chassis and driving wheel and embodying a system of pulleys and a cable anchored to the ground forwardly of the automobile for pulling the same out of a mudhole or the like.

The winding cable drum of the attachment associated with the driving wheel B is shown in detail in Figs. 2 to 7, the same embodying 75 a central drum portion 1 having outwardly directed side flanges 2 and 3 and a central opening 4 to receive the hubs of the wheel B, the drum being secured to the wheel by anchoring bolts and clamps passing through 80 openings 5 extending transversely of the drum as shown in Figs. 1 and 2 and connected to the spokes of the wheel.

A cable 6 is associated with the drums 1 and carries upon one end thereof, a hook 7 85 as shown in Figure 2 that is adapted for detachable engagement with the flange 3 of the drum. To provide for such detachable engagement, the flange 3 is provided with spaced peripheral recesses 8 having divergent side walls 9 providing a restricted entrance opening 10 into which the hook 7 upon the cable 6 is received as shown in Fig. 2 with the hook engaging on the inclined side walls 9 as illustrated. To retain the hook within the recess 8, a tensioned lock bolt is provided for closing the outer end of the recess, the lock bolt embodying a bolt head 11 having the end 12 thereof received in the socket 13 provided in the adjacent side wall 9, the bolt head being positioned adjacent the periphery of the flange 3 to form a continuation thereof as shown in Figs. 4 and 6. A stem 14 is carried by the bolt head 11 and freely extends into the groove 15 formed in the periphery of the flange 3 adjacent the recess 8 and at one side thereof as shown in Figure 4. A coil spring 16 surrounds the pin 14 for normally holding the bolt head 11 in a position traversing the open side of the recess 8. As shown in Figs. 4 and 7, the side walls of the sockets

15 are provided with arcuate slots 17 through which pins 18 carried by opposite sides of the stem 14 projects as shown in Fig. 4, movement of the bolt head 11 being effected 5 by shifting the pins 18 in the slots 17 to displace the bolt heads from the outer side 10 of the recess 8 to permit removal of the hook 7 from the recess. The form of keeper recess for the cable hook 7 may be of the type 10 above described in detail, or if desired open sides recesses 8^a, as shown by dotted lines in Fig. 2 may be provided.

As shown in Fig. 1, the cable 6 extending from the drum 1 passes over a guide pulley 19 depending from the chassis A of the automobile continuing over the pulley 20 and 21 anchored as at 22 to the hook 23 associated with the pulley 20, the hook 23 being secured to the ground entering peg 24 while the pulley 21 carries a staple 25 for engagement 20 with the hook 26 carried by the front end of the chassis A.

With the emergency draft appliance secured to the automobile as above described, 25 and shown in Fig. 1, the wheel B is rotated, the cable 6 to be wound on the drum 1, and by the anchoring of the cable 6 to the peg 24 and the pulley connection between the cable and the hook 26 of the automobile 30 chassis, the cable will be wound upon the drum and the automobile effectively removed from a mud hole or the like. By the provision of a series of recesses 8 or 8^a in the periphery of the drum flange 3, the cable 35 and pulley arrangement may be set up for operation and all slack in the cable 6 taken up by placing the cable hook 7 in the proper recess of the flange 8 or 8^a.

While there is herein shown and described 40 what is believed to be the preferred embodiment

of my invention it is nevertheless to be understood that various forms, modifications and arrangements of the parts may be made without departing from the spirit and scope of the invention as claimed. 45

Having thus described the invention, what I claim as new is:—

1. A draft attachment for automobiles, comprising a drum secured to the hub of the driving wheel, and including side flanges, one of said flanges having a recess therein opening at the periphery of the flange and a tensioned bolt closing the outer side of said recess. 50

2. A draft attachment for automobiles, comprising a drum secured to the hub of the driving wheel, and including side flanges, one of said flanges having a recess therein opening at the periphery of the flange, said flange having a peripheral groove therein 60 at one side of said recess, a tensioned bolt pin positioned in said groove and a bolt head carried by said pin adapted to close the outer side of the flange recess. 65

3. A draft attachment for automobiles, comprising a drum secured to the hub of the driving wheel, and including side flanges, one of said flanges having a recess therein opening at the periphery of the flange, said flange having a peripheral groove therein at 70 one side of said recess, a tensioned bolt pin positioned in said groove and a bolt head carried by said pin adapted to close the outer side of the flanged recess, the flange at opposite sides of said groove having elongated 75 openings therein and operating pins carried by said bolt extending through said openings. 80

In testimony whereof I affix my signature.
MIKE SEPELYAK.
